UNITED STATES PATENT OFFICE.

SAMUEL KAYE, OF COLUMBUS, MISSISSIPPI.

COOLING CHEST.

Application filed January 15, 1923. Serial No. 612,744.

To all whom it may concern:

Be it known that I, SAMUEL KAYE, a citizen of the United States, residing at Columbus, in the county of Lowndes and State of Mississippi, have invented certain new and useful Improvements in Cooling Chests, of which the following is a specification.

My invention relates to an improvement in cooling chests.

10 The object is to provide a cooling chest or refrigerator more particularly adapted for cooling soft-drinks, but which can be utilized for cooling any article of food.

The invention is simple, of few parts, easy 15 to construct, and effective in its results.

In the accompanying drawings:—

Fig. 1 is a vertical longitudinal section;

Fig. 2 is a top plan view with the cover removed;

20 Fig. 3 is a transverse section on line 3—3 of Fig. 1;

Fig. 4 is a view in perspective of the tray;

25 Fig. 5 is a perspective view of the water agitator;

Fig. 6 shows a detail.

A, represents the body of the refrigerator, and 1 is the cover. These are made in the usual way, and insulated to keep out 30 the heat and retain the cold. As an additional means of keeping the interior at as low a temperature as possible, a flexible top 2 may be employed. This may be like the flexible top of a desk or cabinet, made 35 of parallel strips with a backing of flexible material. In fact any covering such as a carpet, rug or blanket might be thrown over the entire cooling-chest as an additional means of retaining the cold. If desired, 40 coils 7 and 8 may be located adjacent to the opposite walls of the interior of the chest and connected by the pipe A' at the bottom for conducting and circulating water for drinking purposes through the cooling-chest, and, when employed, these coils are 45 so arranged that they may be lifted entirely out when the cover is removed for cleaning or any other reason. Inlet and outlet pipes 9 and 10 are connected with

50 the coils 7 and 8, and fit in the grooves 11 and 12 in the sides of the body, immediately below the cover, to allow easy removal of the coils.

When these coils are used, they are held 55 in position by supports 19. In a small box, two of these are sufficient for each coil, and

they are located at opposite ends. More might be employed and located at intermediate points in a larger size chest.

Perhaps the leading feature of my invention is the provision for partially submerging the articles to be kept cool under a body of water maintained at a low temperature. In order to do this, provision is made for holding the ice down to a certain position below the body of water in which the articles to be kept cool are submerged. This may be done by a tray 16, which serves a double purpose, first, as a support for holding the articles at a definite level below the water level, so that they are always kept submerged at a certain point in the cold water; and, second, to hold the ice which naturally rises a little above the water level to a point immediately below and in contact with the bottom of the tray. For this reason, the tray 16 is made of some conductor of cold, such as sheet-metal, and in convenient form. This has ribs 17 bent into it at intervals to give it strength, and its ends are secured to the angle-iron strips 18 as illustrated in Fig. 4. When the water circulating coils 7 and 8 are employed, the ends 15 of these angle-irons 18 rest upon the coils. The supports 19, which bear the weight of the coils and hold them in position and properly spaced, may be bent inwardly at their upper ends to form the hooks 14 in position to come immediately above the ends 15 of the angle-irons, thus holding the tray down against the ice and keeping the ice at the proper level and in immediate contact with the bottom of the tray, so that the maximum degree of cold in the cooling-chest would be on the tray at the point where the articles to be cooled rest.

The cooling-chest is perfectly efficient for its primary purpose without the coils 7 and 8, and if such coils were not used, the sheet-metal lining of the chest might have a flange 25 bent inwardly, as shown in Fig. 6, to form a support for the tray, and any convenient means might be employed to hold the tray down upon the supports.

It is understood that when bottled goods are being cooled, or in fact any other articles, they are placed upon the tray 16. If bottled goods are being cooled as designed, the water level is kept comparatively high, so that they are always kept partly submerged while resting upon the tray, thus utilizing all the cold which the water has

derived from the ice to keep the articles on the tray at the desired temperature. It is understood that solid chunks of ice or cracked ice might be used in the space below the tray, the tray, however, always serving to keep the ice down, as well as supporting the articles to be kept cool.

An agitator consisting of a plunger 20 and a handle 21 (shown in perspective in Fig. 5, and in position in Figs. 1, 2 and 3 in the refrigerator) rests in the space at one end of the cooling chest or refrigerator in position where it may be raised and lowered, from time to time, to agitate the water within the cooling chest or refrigerator in order to equalize the temperature thereof.

A drain pipe 26 is connected with the cooling chest and has a valve 27 therein for opening or closing the drain. This drain normally remains closed, only being opened to drain the water from the chest in order to facilitate the cleaning of the same. An overflow pipe 28 is connected with the drain pipe between the valve and the chest, and has a gooseneck 29 in the upper end thereof to prevent the water from rising above a definite level.

In this way, I have provided a very simple and inexpensive form of refrigerator or cooling-chest well adapted to the purpose of keeping articles resting upon the tray cold; at the same time they are easily accessible from the top of the cooling-chest or refrigerator, which is a desideratum, especially for the dispensing of bottled goods.

I claim:

1. A cooling chest including a body, a tray within the body for holding articles to be cooled, said tray having projections at

the sides thereof, lugs for slidably engaging the upper surface of said projections for holding the tray in position, and means for limiting the downward movement of the tray.

2. A cooling-chest including a body and cover, the body adapted to be partly filled with water and ice, a tray for holding down the ice below the water level, and for maintaining the articles to be cooled partially submerged, ice-water coils arranged vertically at opposite sides of the chest and forming a support for the tray, and supports for the coils having inturned projections at their upper ends for holding the tray down when in position on the coils.

3. A cooling chest including a body, a cover, a tray within the body for holding the articles to be cooled, ice-water coils arranged within the chest and forming a support for the tray, and supports for the coils having inturned projections at their upper ends and ears on said tray for engaging said projections for holding the tray in position on the coils.

4. A cooling chest including a body, a cover, a tray for holding the articles to be cooled, ice-water coils arranged within the chest and forming a support for the tray, inlet and outlet pipes connected with the coils, supports for the coils having inturned projections at their upper ends and ears on said tray for engaging said projections for holding the tray in position on the coils, and overflow and drain pipes connected with the body for draining the water therefrom.

In testimony whereof I affix my signature.

SAMUEL KAYE.
